Primary Examiner—Cynthia E. Ramirez

(57) **CLAIM**

The ornamental design for skid for supporting objects, as shown and described.

DESCRIPTION

FIG. 1 is a top perspective view of skid for supporting objects showing our design;

FIG. 2 is a bottom perspective view thereof;

FIG. 3 is a left side view thereof, the right side view being a mirror image thereof;

FIG. 4 is a top plan view thereof;

FIG. 5 is a front elevation view thereof, the rear elevation view being a mirror image thereof; and,

FIG. 6 is a bottom plan view thereof.
